(57) **CLAIM**

The ornamental design for a heater for semiconductor manufacturing apparatus, as illustrated and described.

DESCRIPTION

FIG. 1 is a top plan view of a heater for semiconductor manufacturing apparatus according to our new design;

FIG. 2 is a bottom plan view thereof;

FIG. 3 is a front view thereof;

FIG. 4 is a back view thereof;

FIG. 5 is a left side view thereof; and,

FIG. 6 is a right side view thereof.
